CLAIM

I claim the ornamental design for a chair, as shown and described.

DESCRIPTION

FIG. 1 is a front left isometric view of a chair of my new design;

FIG. 2 is a front view of the chair of FIG. 1;

FIG. 3 is a rear view of the chair of FIG. 1;

FIG. 4 is a left view of the chair of FIG. 1;

FIG. 5 is a right view of the chair of FIG. 1;

FIG. 6 is a top view of the chair of FIG. 1; and,

FIG. 7 is a bottom view of the chair of FIG. 1.

The broken lines depict portions of the chair that form no part of the claimed design.

1 Claim, 6 Drawing Sheets
